DESIGN FOR A BROOCH OR SIMILAR ARTICLE

Maurice Duvalet, Congers, N. Y., assignor to Van Cleef & Arpels, Inc., New York, N. Y., a corporation of Delaware

Application October 26, 1948, Serial No. 149,294

Term of patent 3½ years

(Cl. D45—19)

To all whom it may concern:

Be it known that I, Maurice Duvalet, a citizen of the United States, residing at Congers, in the county of Rockland and State of New York, have invented a new, original, and ornamental Design for Brooch or Similar Article, of which the following is a specification, reference being had to the accompanying drawing, forming part thereof.

Fig. 1 is a plan view of a brooch or similar article, showing my new design;

Fig. 2 is a side elevation of the embodiment shown in Fig. 1;

Fig. 3 is a front view of same; and

Fig. 4 is a side elevation of same.

I claim:

The ornamental design for a brooch or similar article, substantially as shown.

MAURICE DUVALET.
